Inventor

ROBERT W. JOHNSON,

By *Jack Richmond*

Attorney

UNITED STATES PATENT OFFICE.

ROBERT W. JOHNSON, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

RACK FOR ADHESIVE PLASTER.

Application filed June 23, 1927. Serial No. 200,941.

The invention relates to mountings mainly for hospital use for dispensing adhesive tape or plaster, and it provides an efficient and easily operated rack to accommodate factory 5 filled spools or reels of adhesive tape or plaster, the object being to guard against substitution of inferior or competitive tape or plaster.

The preferred embodiment is illustrated 10 in the accompanying drawings, wherein

Figure 1 is an elevational view of the improved rack assembly.

Fig. 2 is a perspective view of the locking standard in open state.

Fig. 3 is a top view thereof, partly in 15 section.

Fig. 4 is an end view of the same.

According to the invention, there is provided a base 5, which may rest upon a table 20 or like support or be attached to a wall as by screw fastenings 6. The base carries a pair of standards, whereof the standard 7 is equipped with a centering boss 8 and whereof the standard 9 is equipped with a 25 locking boss 10 for a rod or spindle 11 which received a factory filled and locked assembly of variable width adhesive tape or plaster units 12.

The locking boss 10 is divided to provide a 30 releasable half boss 13, which is hinged by a pintle mounting 14 in order that it may assume the position, Fig. 2, for the application or removal of the spindle 11. The movable half boss, 13, is provided with an end- 35 wise ranging screw threaded socket 15, which, when the half boss is in closed position, is adapted and arranged to register with a threaded opening 16 in the standard

body and to be engaged and so locked by a thumb screw 17.

In hospitals and the like places where devices of this nature find their chief utility, the plaster is mounted and dispensed by female attendants possessing little or no knowledge of mechanics, and the instant 45 problem is to devise and provide a plaster reel mounting which will fulfill the primary office of preventing substitution and yet be simple enough to be foolproof.

Having described my invention, I claim 50

1. A rack for factory filled adhesive plaster, including elements for centering and locking a plaster carrying spindle, comprising a base and a pair of standards rising therefrom and having integral bearings for 55 the spindle, one of said bearings having boss divisions whereof one is shiftable laterally to provide a radial passway for the spindle, and means penetrating the standard and effective to lock and unlock the shiftable boss 60 element.

2. A rack for factory filled adhesive plaster, including elements for centering a plaster carrying spindle, one of said elements being a standard having hollow boss 65 sections whereof one is movable with relation to the other to provide a radial passway for the spindle, said movable section having an endwise ranging screw-threaded socket which in the closed position of the 70 section is adapted to register with an opening in the standard body, and a thumb screw penetrating said opening for engagement with said socket.

In testimony whereof I affix my signature.

ROBERT W. JOHNSON.
